UNITED STATES PATENT OFFICE.

ERNESTO LUCERINO, OF NEW YORK, N. Y.

STOVE OR RANGE.

1,119,182.

Specification of Letters Patent.

Patented Dec. 1, 1914.

Application filed November 20, 1913. Serial No. 802,040.

To all whom it may concern:

Be it known that I, ERNESTO LUCERINO, a citizen of Italy, and residing at New York, in the county of New York and State of New York, have invented certain new and useful Improvements in Stoves or Ranges, of which the following is a specification, such as will enable those skilled in the art to which it appertains to make and use the same.

This invention relates to stoves or ranges, and the object thereof is to provide an improved device of this class designed for the use of either coal or gas, as may be desired, one end portion thereof being adapted for use as a gas range or stove, and the other end portion as a coal stove, said device being also provided, centrally thereof, with a water boiler adapted to be heated from or by means of, either the gas stove or range portion or the coal stove or range portion.

The invention is fully disclosed in the following specification, of which the accompanying drawings form a part, in which the separate parts of my improvement are designated by suitable reference characters in each of the views, and in which:

Figure 1 is a perspective view of my improved stove or range;—Fig. 2 a vertical longitudinal section thereof;—Fig. 3 a transverse vertical section on the line 3—3 of Fig. 2;—Fig. 4 a similar section on the line 4—4 of Fig. 2;—Fig. 5 a similar section on the line 5—5 of Fig. 2, and;—Fig. 6 a similar section on the line 6—6 of Fig. 2.

In the practice of my invention, I provide a stove or range *a* which is oblong in form and rectangular in cross section, and in the central portion of which, or approximately the central portion of which, is a transverse water boiler *b*.

For the purpose of this description, the end *a*² of the stove or range will be called the front end, and the end *a*³ the back end thereof, and in carrying my invention into effect, the front end portion *a*² is provided in the top thereof with a warming or heating oven *c*, and in the bottom thereof with a gas oven *c*², divided by horizontal partitions *c*³ into separate compartments, and in the bottom of which is placed a gas burner *d*, and in the top of which is placed a supplemental gas burner *d*².

The burners *d* and *d*² are supplied by a main gas supply pipe *e* having branches *e*², and the front top portion of the stove or

range is open and provided with the usual open grille or spider work *a*⁴ beneath which is placed the usual gas burners *d*³ which are supplied with gas by a supplemental pipe *e*³ connected with the main gas supply pipe *e*, and the supplemental gas pipes *e*² and *e*³ are provided with valves *e*⁴.

The boiler *b* is provided with a water supply pipe *b*² which communicates with the top back portion thereof, and said boiler is also preferably provided with a discharge faucet *b*³ by which water may be drawn off, when desired, for any purpose.

Connected with the top and bottom portions of the boiler *b*, preferably through the back of the stove or range, are water circulating pipes *f* and *f*² which are formed into, or connected with a loop or coil *f*³ which extends along the back of the front portion of the stove or range, and are formed into, or connected with, a supplemental loop or coil *f*⁴ located in a chamber *a*⁵ between the gas oven *c*² and the front wall of the stove or range, and beneath which is placed a gas burner *g* which is supplied by a supplemental pipe *g*² connected with one of the supplemental gas pipes *e*² and provided with a valve *g*³. The ovens *c* and *c*² are provided in one side of the stove or range with doors *h* and *h*².

In the back or back end portion of the stove or range is a firebox *i* having a grate *i*² below which is an ash pit *i*³, and forwardly of the firebox *i*, or between the firebox and the boiler *b*, is an oven *j* having partitions *j*² and provided with a door *j*³. The oven *j* is inclosed by a horizontal top flue passage *k*, a vertical inner flue passage *k*² between the boiler *b* and said oven, and a horizontal bottom flue passage *k*³, and in the use of this part of the device, the hot products of combustion in the firebox *i* pass forwardly over the top of the oven *j* downwardly at the front thereof and backwardly beneath said oven, as indicated by the arrows *x*, and from the bottom flue passage *k*³ said products of combustion pass backwardly and through a flue *k*⁴ located at the back of the stove or range and provided with a pipe *k*⁵.

The firebox *i* is provided with the usual door *m*, and the ash pit *i*³ with the usual door *m*², and in one side of the stove or range, preferably just below the door *j*³ of the oven *j*, is an air register *m*³ which communicates with the flue passage *k*³. The

door m of the firebox i is also provided with an air register m^4 , and by means of the air registers m^3 and m^4 , the fire in the firebox i may be controlled, as may also the temperature of the oven j .

With this construction, it will be seen that one end portion of my improved stove or range may be used as a gas stove or range, and the other as a coal stove or range, and the boiler b or the water therein may be heated from either end portion of said stove or range, when said end portion is in use, and said boiler or the water therein may be heated by means of the gas burner g and the circulating pipes and coils f , f^2 and f^3 whenever desired, without the use of either end portion of said stove or range for cooking or other purposes.

Any suitable means may be provided for supplying air to the gas burners d and d^2 , and said burners may be of any form or construction as may also the burners d^3 and g , and various changes in and modifications of the construction herein shown and described may be made, within the scope of the appended claims, without departing from the spirit of my invention or sacrificing its advantages.

Having fully described my invention what I claim as new and desire to secure by Letters Patent is:—

1. A stove or range one end portion of which is provided in the bottom thereof with a gas oven having top and bottom burners and above which is a heating oven, the other end portion of said stove or range being provided with a firebox inwardly of which is an oven around which the products of combustion from said firebox are adapted to pass, said stove or range being also provided centrally thereof with a boiler adapt-

ed to be heated by either end portion of said stove or range when in use, said boiler being also provided with independent means whereby it may be heated.

45

2. A stove or range one end portion of which is provided with a gas heated oven and the other end portion with a fire-box inwardly of which is an oven around which are flues through which the products of combustion from the fire-box pass, said stove or range being also provided centrally thereof with a boiler one wall of which forms a wall of the gas oven, and another wall of which forms a wall of said flues.

50

3. A stove or range one end portion of which is provided with a gas heated oven and the other end portion with a fire-box inwardly of which is an oven around which are flues through which the products of combustion from the fire-box pass, and a water boiler placed between the gas heated oven and said flues and adapted to be heated by either or both.

60

4. A stove or range one end portion of which is provided with a gas heated oven and the other end portion of which is provided with a fire-box inwardly of which is an oven adapted to be heated from the fire box, and a water boiler placed transversely of said stove or range and between said ovens and adapted to be heated by either or both.

70

In testimony that I claim the foregoing as my invention I have signed my name in presence of the subscribing witnesses this 19th day of November, 1913.

75
